[57] **CLAIM**

The ornamental design for a reflective identification tag, as shown and described.

DESCRIPTION

FIG. 1 is a front elevation view of the reflective identification tag of the present invention;

FIG. 2 is a back elevation view of the reflective identification tag of FIG. 1;

FIG. 3 is a left side elevation view of the reflective identification tag of FIG. 1;

FIG. 4 is a right side elevation view of the reflective identification tag of FIG. 1;

FIG. 5 is a top plan view of the reflective identification tag of FIG. 1;

FIG. 6 is a bottom plan view of the reflective identification tag of FIG. 1; and,

FIG. 7 is a top, front, right side perspective view of the reflective identification tag of FIG. 1.

The broken lines are shown for illustrative purposes only and form no part of the claimed design.
